THERAPEUTIC LAMP

Mortimer Marks, also known as Mortimer Marks
Ginsberg, Brooklyn, N. Y.

Application July 30, 1931, Serial No. 553,911

9 Claims. (Cl. 174—177)

This invention relates primarily to therapeutic lamps and is directed more particularly to a lamp of this character employing an electric arc for the production of so-called ultraviolet light to be used for therapeutic treatments and for the so-called sun ray treatments.

Aside from its use in the art of therapeutics, the invention, however, embodies novel and important features relating to the controlling of the feed of electrical current across a gap to form an arc and this phase of the invention is adapted for general application.

In arc lights, considerable difficulty has heretofore been encountered in controlling the space between carbons at the arc. There has been an ever present tendency of the movable electrode or carbon when partaking of that movement necessary to draw the arc to overtravel with the result that the light has been intermittent and of relatively short duration.

One of the objects of this invention is to control the movable electrode in such manner that when the arc is drawn, this electrode will not normally move a greater distance from the fixed electrode than is necessary to produce the desired arc and will be maintained in proper arcing relation to the fixed electrode until the electrodes are eroded or burnt away to such extent as will require a feed of the movable electrode to effect another arcing operation.

An important feature of this invention resides in the fact that the so-called arcing operations are of relatively long duration and are not rapidly intermittent as has heretofore generally been the case, where relatively fixed and movable electrodes are employed and particularly where such movable electrodes have been controlled by a magnetic flux circuit.

Another feature of the present invention resides in time controlled apparatus whereby the duration of operation of the lamp may be controlled and regulated to the end that the lamp may be set for a predetermined period of operation, to be automatically turned off or de-energized at the conclusion of such period.

In one of its preferred, practical forms, the lamp of this invention comprises a fixed and movable electrode, the latter of which is carried by and supported on the armature of a solenoid which is included in circuit with the electrodes so that the energizing current operates both the solenoid and causes the arc. The core of the solenoid is provided with ratchet teeth disposed longitudinally of the core and with these ratchet teeth cooperates a pawl which conveniently may

be made in the form of a leaf spring. The pawl and ratchet arrangement thus provided allows of the feed of the movable electrode in the direction of the fixed electrode, but limits the retrograde movement of the movable electrode to a distance which will permit the current to normally jump the gap, so that when the core of a solenoid is energized, the arc is drawn and the spacing of the electrodes at the arc will remain substantially constant until by erosion or burning away the space becomes too great for the current to pass whereupon the movable electrode will be fed by gravity into contact with the fixed electrode to cause a redrawing of the arc for a further period of continuous operation.

The electrical circuit through the solenoid may, according to this invention, include a time switch electrically controlled as hereinafter more fully described by an overload, underload, or weakening of the flux circuit to break the electrical circuit through the apparatus at the conclusion of a predetermined period of operation.

Features of the invention, other than those adverted to, will be apparent from the herein-after detailed description and claims, when read in conjunction with the accompanying drawing.

The accompanying drawing illustrates different practical embodiments of the invention, but the constructions therein shown are to be understood as illustrative, only, and not as defining the limits of the invention.

Figure 1 is a central vertical section through a lamp embodying the present invention, this section being taken in the plane of the line 1—1 of Figure 2.

Figure 2 is a front elevation of the structure shown in Figure 1, with the addition of a time stage.

Figures 3 and 4 are wiring diagrams showing modified forms of current control.

Referring to the drawing, 1 indicates a casing which may conveniently be made as shown in the form of a reflector across the front of which is provided a screen 2 for protective purposes. The casing is mounted upon a suitable base 3 and in the lower portion of the casing is a holder 4 for the fixed electrode 5 which is preferably a conventional carbon electrode.

The upper portion of the casing carries a boss 6 in which is supported an upstanding tubular section 7 and on this tubular section is carried a coil 8 of a solenoid. The tubular section 7 is of non-magnetic material such, for example, as brass and it extends upwardly through the coil 8 as shown, so as to mount and support the coil 55

thereon. The opposite ends of the coil are preferably covered with caps 9 and 10 which may be either of magnetic or non-magnetic material, but are, in the preferred form of the invention, 5 of magnetic material, such as soft iron for reasons hereinafter more fully explained.

The core of the solenoid is indicated at 11. It is tubular in form and is provided therein with a bushing 12 insulated from the tubular core 10 by insulating sleeve 13. The lower end of the bushing is flanged outward in a radial direction while the upper end of the bushing extends above the tubular core and is exteriorly threaded to receive a piece of tubular insulation 14 which, 15 when screwed down tightly on to the core, will tightly clamp the insulating sleeve 13 in position.

On the inside of the bushing 12 is a leaf spring 15 and the movable electrode or carbon 16 is adapted to be held resiliently within the core 10 and its associated parts by frictional engagement 20 with the interior of the bushing and with the leaf spring 15. Thus to insert the movable electrode 16, it is simply forced downwardly through the insulating section 14 past the spring 15, 25 whereupon the spring grips the electrode and holds it firmly in place. The central electrode is thus carried on and supported by the core of the solenoid and is movable axially with said core.

30 The exterior of the core 11 is provided as shown in Figure 1 with a longitudinally arranged series of teeth 17 which collectively form a ratchet extending for substantially the full length of the core, and mounted upon one of the caps 35 10 or in any other suitable and convenient location is a pawl 18 shown in the form of a leaf spring. This leaf spring is attached to the cap 10 by means of rivets 19 or in any other suitable way and the nose 20 of the spring extends 40 through a slot 21 in the tubular section 7 in a manner to engage and cooperate with the ratchet 17. The ratchet is so formed as to permit the core to move idly and freely in a downward direction, but if upon retrograde movement the 45 particular tooth with which the pawl is juxtaposed will engage with said pawl and the movement of the core in an upward direction will be arrested. If a rigid pawl is used, the teeth of the ratchet should be sufficiently far apart to 50 permit a proper arc to be drawn before the pawl arrests the core, but when a spring pawl is used as shown, the slot 21 in the tubular section 7 may be made of such length as to control the movement of the pawl and to thereby cause a positive 55 arrest of the core after a predetermined retrograde movement. For example, the nose of the pawl may in normal position be at the lower end of the slot 21. In such a case, the retrograde movement of the core will be controlled by the 60 upper end of the slot because the core will move upwardly and slightly flex the spring pawl until the pawl engages with the upper end of the slot 21 whereupon further upward movement will be positively arrested.

65 If it be assumed therefore that the solenoid coil is arranged in series with the electrodes 5 and 16 as shown in Figure 1, the current which is caused to pass through the electrodes for the production of the arc will serve also to energize the 70 solenoid, drawing the core upwardly to draw the arc while the pawl controls the extent to which the core may be retracted for this purpose so that there may be no upper overtravel of the core which would result in too wide a spacing of the electrodes at the gap. It will of

course be apparent, however, that when the electrodes burn away or erode sufficiently to break the current in the circuit 22, then the solenoid will be de-energized and the core will feed downwardly to present the next tooth to the pawl. 5

The apparatus which I have described as particularly useful in therapeutic lamps, but it may be employed in any arc lighting circuit without departing from this invention. Furthermore, there are times when it would be desirable to 10 have different arc lighting circuits operate for predetermined periods of duration with subsequent automatic shut off. This is particularly true, for example, in connection with therapeutic lamps where there is a possibility of serious effects 15 due to too prolonged treatment. For this reason, I have provided novel and efficient means for controlling the time or duration of the operation and in Figure 2, I have shown means for accomplishing this result. In this figure, the caps 9 20 and 10 should be of magnetic material, preferably soft iron. The lower cap is provided with a bracket 23 to which an arm 24 is pivoted at 25. This arm is of magnetic material such as soft iron and the free end 26 of the arm is normally 30 retracted from the cap 9 by means of a leaf spring 27. Positioned adjacent the inside of the arm 24 is a fixed contact 28 and a movable contact 29. The contact 29 normally tends to move in a direction away from the contact 28, so that when the arm 24 is swung outwardly away from the cap 9, the contact 29 will disengage from the contact 28. The contacts 28 and 29 are included in the circuit which includes the electrodes and the solenoid coil. Thus, when these 35 contacts are separated, the circuit will be de-energized.

The theory of operation of the structure shown in Figure 2, is that when the core of the solenoid is near or adjacent its magnetic center within 40 the coil, the magnetic flux circuit of the solenoid will comprise the soft iron core, the cap 9, arm 24 and the lower cap 10, so that there will be a substantially closed flux circuit to the solenoid. As long as this flux circuit is strong enough to 45 overcome the tension of the spring 27, the arm 24 will be held in the position shown in Fig. 2 by the flux circuit. However, as the lamp operates and the core feeds downwardly through a period of time, there will come a time when the core 50 will be moved downwardly so far away from the upper cap 9 as to so weaken the flux circuit that it will no longer be strong enough to retain the arm 24 in this position and thereupon the spring 27 will throw the arm in an outward 55 direction and break the circuit at the contacts 28 and 29, thus de-energizing the entire lamp.

My experience has shown that the erosion or burning away of the electrodes occurs at a substantially uniform rate, so that it can be well 60 determined how long a predetermined portion of the length of the electrode will be consumed within a predetermined period. Thus by attaching to the core or to the electrode an adjustable indicator 30 and providing a time scale 31 over 65 which this indicator may travel, it is possible to initially set the parts so that the lamp will function for a predetermined time at the expiration of which the core will have moved downwardly far enough to release the arm 24 and 70 shut off the lamp.

Another way in which the timing of the operation may be accomplished is shown diagrammatically in Figure 3. In this figure, an overload release indicated at 32 is included in the circuit 75

in series with the carbons and the solenoid. Figure 3 shows a modified form of timing apparatus. This operates on the principle that when the armature descends to a certain point, the magnetic pull is insufficient to support the weight of the core or armature. When this occurs, the carbons meet but no arc is drawn. As the carbons remain in contact, the voltage drop across the carbons is practically eliminated and the heavier current which is thereby caused to flow may be utilized to operate any well known and suitable form of overload release switch, indicated at 32, which is included in the circuit of the lamp. The timing is accomplished by predetermining the height of the armature at the commencement of the operation, so that it will take a certain length of time for the carbons to burn away and permit the armature to descend to the critical point where the carbons will meet, but the magnet will be of insufficient strength to raise the armature. Almost immediately the overload release will operate and the feed of current through the apparatus will cease.

Most of hand operated therapeutic arc lamps now in use utilize fixed electrodes set at an angle as shown in Figure 4. I have found that I can time the operation of such a lamp by using an underload release switch as shown in this figure. The switch arm 33 is pivoted at 34 and constitutes the armature of magnet 35. A spring 36, the tension of which may be adjusted by a set screw acts to normally retract the arm 33 from the magnet core 35. When the current has burned away, the carbons to, e. g., the line 37, the current in the circuit will have been sufficiently decreased to decrease the pull of the magnet 35 on the arm 33 which will be acted upon by spring 36 to break the circuit. The timing may be controlled or determined by regulating the tension of the spring 36 so as to draw the handle away after the current has decreased to a predetermined extent. Since the burning of the carbons is at a substantially uniform height, I may thereby obtain approximately correct timing.

Having thus fully described the invention, what I describe as new and desire to secure by Letters Patent is:

1. In an apparatus of the character described, a solenoid having a core, a movable electrode carried by the core, a stationary electrode positioned to cooperate with the movable electrode to permit of the formation of an arc therebetween, ratchet teeth carried by the armature, and a pawl mounted in relatively stationary position and adapted to cooperate with said ratchet teeth to permit the unrestricted feed of the movable electrode in the direction of the fixed electrode, but to limit retrograde movement of the movable electrode to a predetermined maximum.

2. In an apparatus of the character described, relatively fixed and movable electrodes, a solenoid having a core on which the movable electrode is supported, and pawl and ratchet means for permitting the feed of the movable electrode in the direction of the fixed electrode but to limit retrograde movement of the movable electrode to a predetermined maximum.

3. In an apparatus of the character described, fixed and movable electrodes, a solenoid core secured to and supporting the movable electrode, said core provided with a series of ratchet teeth, a solenoid coil surrounding said core for energizing the same and a pawl mounted stationary with respect to the coil and coacting with the ratchet teeth of the armature to permit the

armature to feed the movable electrode in the direction of the fixed electrode but to limit the retrograde movement of the movable electrode to a predetermined maximum.

4. In an apparatus of the character described, relatively movable electrodes with means for moving them apart for the purpose of drawing an arc between them, and pawl and ratchet means for restricting the separating movement of the electrodes to a predetermined maximum.

5. In an apparatus of the character described, fixed and movable electrodes, an armature secured to and carrying the movable electrode, a coil for operating said armature to move the movable electrode for the purpose of drawing an arc, pawl and ratchet means cooperating with the armature to limit the gap between the electrodes to a predetermined maximum, an electric circuit including the electrodes and the coil, and a switch included in said circuit, and an over-load relay switch including said circuit.

6. In an apparatus of the character described, a solenoid comprising a core and a coil, the latter of which is provided at its opposite ends with magnetic parts adapted to form with the core a portion of a flux circuit, a magnetic bridge member adapted to normally bridge said magnetic parts to form with the metallic parts and core a magnetic flux circuit when the core is at or adjacent its magnetic center within the coil, an electrode carried by said core, a circuit including the coil and electrode, a switch also included in said circuit, and positioned to be operated by the magnetic bridge, and means for retracting the bridge from engagement with one of the magnetic end pieces of the coil, and opening the switch when the core descends appreciably below its magnetic center.

7. A therapeutic lamp embodying a pair of relatively movable electrodes, an armature for carrying one of them, an electric circuit including said electrodes, and means affixed to the armature electrode to permit the shifting of the said electrode relative to its armature for the purpose of effecting timing, and a time scale cooperating with said means.

8. A therapeutic lamp embodying a pair of relatively movable electrodes, electromagnetic means for shifting one of said electrodes with respect to the other for the purpose of drawing an arc with consequent erosion of the electrodes, said electromagnetic means including a coil and an associated armature by which armature one of said electrodes is carried, a circuit including said coil and electrodes, means also included in said circuit for breaking the circuit when the armature is sufficiently removed, through continued erosion of the electrodes, from the magnetic flux circuit to cause a predetermined weakening of such flux circuit, and manually operable means for axially shifting one of said electrodes in a direction to return the armature to substantially the magnetic center of the coil.

9. A therapeutic lamp embodying a pair of relatively movable electrodes, electromagnetic means for shifting one of said electrodes with respect to the other for the purpose of drawing an arc with consequent erosion of the electrodes, said electromagnetic means including a coil and an associated armature by which armature one of said electrodes is carried, a circuit including said coil and electrodes, means also included in said circuit for breaking the circuit when the armature is sufficiently removed, through continued erosion of the electrodes, from the mag-

netic flux circuit to cause a predetermined weakening of such flux circuit, manually operable means for axially shifting one of said electrodes in a direction to return the armature to substantially the magnetic center of the coil, and a time scale associated with said manually operable means for the purpose of regulating the electrodes and armature to such relation as will per-

mit of a predetermined elapsed period of time of operation before the armature has moved into a position to cause said circuit breaking means to break the circuit through the coil and electrodes.
